US00D915474S

(12) **United States Design Patent** (10) Patent No.: **US D915,474 S**
(45) Date of Patent: **** Apr. 6, 2021**

(54) **REFRIGERATOR**

(71) Applicant: **LG ELECTRONICS INC.**, Seoul (KR)

(72) Inventor: **Insun Yeo**, Seoul (KR)

(73) Assignee: **LG Electronics Inc.**, Seoul (KR)

(**) Term: **15 Years**

(21) Appl. No.: **35/508,580**

(22) Filed: **Jul. 24, 2019**

(80) **Hague Agreement Data**

Int. Filing Date: **Jul. 24, 2019**

Int. Reg. No.: **DM/205759**

Int. Reg. Date: **Jul. 24, 2019**

Int. Reg. Pub. Date: **Feb. 14, 2020**

(30) **Foreign Application Priority Data**

Jan. 25, 2019 (KR) 30-2019-0003917
